United States Patent Office

Des. 225,016
Patented Oct. 31, 1972

225,016

BUILDING TOY OR SIMILAR ARTICLE

Arthur Halpern, New York, N.Y., assignor to M. I. Sales,
Inc., New York, N.Y.

Filed Mar. 23, 1971, Ser. No. 127,443

Term of patent 14 years

Int. Cl. D21—01

U.S. Cl. D34—15

FIG. 1

FIG. 4

FIG. 2

FIG. 5

FIG. 3

FIG. 1 is a top plan view of the building toy or similar article embodying my new design;

FIG. 2 is a side elevational view thereof;

FIG. 3 is a partial side elevational view thereof at another angle;

FIG. 4 is a partial side elevational view thereof taken at another angle; and

FIG. 5 is a bottom plan view thereof.

I claim:

The ornamental design for a building toy or similar article, substantially as shown.
